ROOF COVERING AND METHOD OF MANUFACTURING SAME

Albert C. Fischer, Chicago, Ill., assignor to The
Philip Carey Manufacturing Company, a cor-
poration of Ohio

Application June 25, 1928, Serial No. 288,302

5 Claims. (Cl. 108—6)

This invention relates to weatherproofing ele-
ments, particularly prepared sheet roofing, and
aims to provide a plurality of layers suitable for
being laminated into a composite covering on
the job without employing any agent for attach-
ing the sheets other than the prepared sheets
themselves.

The invention consists in the features, com-
binations, and arrangements hereinafter de-
scribed or claimed, for carrying out the above
stated object, and such other objects as will
hereinafter appear.

For a better understanding of the invention
reference may be made to the accompanying
drawing, in which

Fig. 1 is a perspective view of a roofing roll
embodying the invention, and

Fig. 2 is a cross-sectional view of a roof sec-
tion showing the invention applied to a roof
deck.

In general the invention comprises a plurality
of waterproofing sheets which are so prepared
that they may be readily adhered into a com-
posite laminated structure. In building up this
structure, at least three sheets should be em-
ployed, but more may be used if a thicker cover-
ing is desired. Of these sheets one comprises
a foundation which is first attached to the sur-
face to be covered, another sheet is normally
adhesive on both faces and may be conveniently
referred to as a wet sheet. After the wet sheet
is attached to the foundation sheet an adhesive
surface is provided for receiving the third or
weather sheet, this latter being preferably sur-
faced on its weather side with granular material
partially embedded therein. Should a com-
posite covering be desired thicker than that pro-
vided by the three layers, then any additional
number of wet or foundation sheets could be
included between the foundation and weather
sheets.

More specifically described, the base sheet 1 is
a saturated felt coated on one or both sides with
a layer 2 of asphalt. A small amount of pow-
dered material such as talc may be dusted over
the coating, altho it is preferable to leave one
face free so that it will be in a more receptive
condition for bonding with the wet sheet 3. The
wet sheet 3 is normally adhesive or sticky at
ordinary temperatures, in which condition it will
readily adhere to the other sheets. The mastic,
saturant or coating 4, as the case may be, of this
wet sheet is in a condition which has solvent
action, and by reason of such solvent action will
bind itself to adjacent layers in which the as-

phalt is of a harder nature. The weather sheet
5 may be a plastic layer or a saturated felt
coated with bituminous material 6. One face
may be surfaced with granular material such
as slate, stone, gravel or like particles 7, partially
embedded to provide additional weather material
on the exposed side.

These sheets may be rolled and shipped in
separate packages, as is customary in roll roof-
ing, and properly marked to indicate the various
kinds, such as the foundation sheet, wet sheet,
or weather sheet. To keep the wet sheet in the
proper adhesive condition in which it was pre-
pared, it is preferably covered with an oilproof
wrapper waxed or silicate coated as at 8. If
it is not desirable that each square of roofing
be shipped in three separate packages, the wet
sheet may be wrapped in an oilproof covering
and then rolled within the other sheets. In
this manner three squares of roofing would be
placed in one roll 9. Additional intermediate
sheets, such as the base and wet sheets may be
included if more than a three-ply roof is desired.
However, it is preferable that the sheets be suf-
ficiently heavy to give an adequate covering with
three plies of the roofing material applied to a
base or roof deck 10 in the manner illustrated
in Fig. 2 of the drawing.

While I have referred to the three layers as
sheets, it will be understood that the weather 85
sheet may be in the form of individual roofing
elements laid in overlapping relation or in the
form of a plastic coating layer applied directly
to the wet sheet. All of the sheets will be so
laid as to break joints with each other.

Obviously the invention is not limited to the
details described, all of which may be variously
modified. Moreover it is not indispensable that
all features of the invention be used conjointly
as certain features may be employed to advan- 95
tage in various different combinations and sub-
combinations.

Having described my invention, I claim:

1. The method of manufacturing self-adher-
ing roofing units characterized by fabricating a 100
plurality of individual sheets comprising a bitu-
minous coated foundation sheet, a weather sur-
facing sheet, and a securing sheet provided on
both faces with a normally sticky adhesive coat-
ing adapted to bond with the first mentioned 105
sheets when interposed between same in a built-
up roof covering.

2. A roofing package containing a self-adher-
ing roofing unit which comprises a foundation
sheet, a weather-surfacing sheet, and a securing 110

sheet provided on both faces with a normally sticky adhesive coating which is adapted to bond with the foundation and weather sheets, all of which are superposed with the securing sheet interposed between the other sheet elements.

3. A roofing package containing a self-adhering roofing unit which comprises a foundation sheet, a weather surfacing sheet having one face covered with granular material, and a securing sheet provided on both faces with a normally sticky adhesive coating which is adapted to bond with the foundation and weather sheets, all of which are superposed with the securing sheet interposed between the other sheet elements.
- 10 5. The method of forming a built-up roof covering characterized by applying to the surface to be covered a bituminous coated foundation sheet, applying to the foundation sheet a bonding layer provided on both faces with a normally sticky adhesive coating, and overlaying the bonding layer with a weather exposed sheet.
- 15 6. The method of forming a built-up roof covering characterized by applying to the surface to be covered a bituminous coated foundation sheet, applying to the foundation sheet a bonding layer provided on both faces with a normally sticky adhesive coating, and overlaying the bonding layer with a weather exposed sheet.
